(57) **CLAIM**

The ornamental design for a pedicure basin base as shown and described.

DESCRIPTION

FIG. 1 is an upper side perspective view of the pedicure basin base according to my design;

FIG. 2 is a left side elevation view thereof;

FIG. 3 is a right side elevation view thereof;

FIG. 4 is a front elevation view thereof;

FIG. 5 is a rear elevation view thereof; and,

FIG. 6 is a top plan thereof.

The broken lines in the drawings illustrate portions of the pedicure basin base that form no part of the claimed design. A bottom plan view is not shown, and there is no claim to the bottom plan view.

1 Claim, 6 Drawing Sheets
